UNITED STATES PATENT OFFICE

RITA BERMAN, OF NEW YORK, N. Y.

DESIGN FOR A BED DESK

Application filed April 7, 1932. Serial No. 43,476. Term of patent 3½ years.

To all whom it may concern:

Be it known that I, RITA BERMAN, a citizen of the United States, residing at New York, county and State of New York, have invented a new, original, and ornamental Design for a Bed Desk, of which the following is a specification, reference being had to the accompanying drawing, forming part thereof.

The figure is a perspective view of the bed desk.

I claim:

The ornamental design for a bed desk, as shown.

RITA BERMAN.
